UNITED STATES PATENT OFFICE.

ROBERT O. HENDRICKSON, OF RACINE, WISCONSIN, ASSIGNOR TO J. I. CASE PLOW WORKS COMPANY, OF RACINE, WISCONSIN, A CORPORATION OF DELAWARE.

AIR CLEANER FOR INTERNAL-COMBUSTION ENGINES.

Application filed April 20, 1921. Serial No. 463,074.

To all whom it may concern:

Be it known that I, ROBERT O. HENDRICKSON, a citizen of the United States, residing at Racine, in the county of Racine and State 5 of Wisconsin, have invented certain new and useful Improvements in Air Cleaners for Internal-Combustion Engines, of which the following is a specification.

When the air employed for combustion in 10 internal combustion engines is taken directly from the atmosphere to the carburetor or to the engine cylinder it is apt to be charged with dirt and grit which is very injurious to the engines, accumulating therein and 15 causing undue wear. It is the purpose of the present invention to provide a means for filtering the air before it reaches the carburetor or the engine and thus remove the grit and dirt therefrom materially prolonging 20 the life of the engine and the periods between repairs.

In the drawing accompanying and forming part of this application I have shown and in the following specification described 25 a preferred form of the invention; it is to be understood however, that the specific disclosure is for the purpose of exemplification only and that the scope of the invention is defined in the following claims in 30 which I have endeavored to distinguish it from the prior art so far as known to me without however, relinquishing or abandoning any portion or feature thereof.

In the drawings Fig. 1 is a side elevation 35 of an engine of ordinary type to which my invention has been applied; Fig. 2 an end elevation partly in section of the preferred form of my invention and Fig. 3 a vertical section through same on a plane perpendicular to that of Fig. 2.

In the preferred form of the invention shown the main body of the device is preferably in the nature of a casting 4 which is formed or provided at 5 with a chamber 45 which, in use, is filled or packed with a body 6 of wool or other similar fibrous-porous or absorbent material. In the specific construction shown the body of wool is supported upon a screen 7 and is packed 50 between the same and a perforated horizontal wall 8, perforations in which serve for the admission of air. At 9, Fig. 2, is a cover plate for closing the opening through 55 which the fibrous material is packed into chamber 5. The air to be cleaned enters the

device through an orifice 10 which preferably is connected to an air heater 11, (see Fig. 1), surrounding the exhaust manifold whereby the air is heated. The orifice 10 communicates with a vertical passage 12 extending to the bottom of the casting and opening at 13 into a flaring passage 14 by which the air is conducted to a horizontal passage 15 immediately above the perforated partition 8.

The casting is formed with a chamber 16 below that in which the wool or other fibrous material is confined and which receives the air after it is filtered through the wool. An outlet nozzle 17 for the air projects into 70 the chamber 16 and is flared at 18 and provided with an internal annular rib 19 for a purpose which will appear. Beneath the outlet chamber 16 is an oil chamber 20 which communicates with chamber 16 through a 75 narrow passage 21. The oil chamber 20 is separated from the flaring passage 14 by wall 22 which is perforated at 23. The oil chamber is filled with oil through a filling opening 24 provided for this purpose. The 80 opening or openings 23 are somewhat above the bottom of the chamber 20 so that the dirt contained in the oil can settle to the bottom and may be drawn off from time to time through the plugged opening 26. A transverse partition 27 extends across the oil chamber at substantially the middle thereof as seen in Fig. 3, but terminates somewhat short of the bottom of the chamber so that 85 there is a free passage through the partition, the purpose of which is to reduce splashing of the oil.

The operation of the device will now be apparent. The air heated in the stove 11 enters the passage 10 due to the suction of the engine and passing through the opening 13 rushes up the passage 14. In so doing it carries with it considerable amounts of the oil issuing through the openings 23 and the oil is deposited in the fibrous or absorbent material as the air is drawn through the latter. Thus the fibrous material is kept saturated with oil which drips therefrom into the air outlet chamber 16 and finally reaches the oil chamber again through the opening 21. The grit and dirt contained in the air are separated therefrom by the oil saturated fibre and the cleaned air entering the chamber 16 is drawn off through the outlet 17, the ribs or beads on the flared 110

inner end of which serve to intercept any drops of oil which may be entrained by the air. Obviously the enlargement of the outlet at the entering end and the enlarged space about the edges of the same very greatly reduce the speed of the air at this point so that it readily deposits any oil which it may contain.

I claim:

- 10 1. An air cleaner comprising a filter chamber having an air inlet and an air outlet, fibrous material in said chamber, an oil chamber beneath the same to receive the oil dripping from said fibrous material, an air 40 passage adjacent the oil chamber and leading to the chamber containing the fibrous material, there being an unobstructed passage for oil between said chamber and said air passage, and an outlet for air intermediate the 45 filter and oil chamber.
20 2. In a device of the class described, a casing, a filter chamber in the upper part thereof containing a fibrous mass, an oil chamber for receiving oil from the fibrous 50 mass located in the bottom of the chamber, an air chamber intermediate the filter and oil chambers and communicating with both, an air outlet communicating with said air chamber, a substantially vertical air passage 55 60 communicating adjacent its bottom with the oil chamber, and an air passage communicating with the lower end of the first said passage and with the upper end of the filter chamber.
30 3. In a device of the class described, a casing having a mass of filtering material therein, an air chamber below said mass, an air outlet for conducting the air from said chamber, an oil chamber below said air chamber.

ber and communicating therewith and receiving oil therefrom, an air inlet passage adjacent the oil chamber, there being unobstructed openings to permit the oil from the oil chamber to flow into the air passage.

4. In a device of the class described, a casing, a filter chamber within the casing having upper and lower perforated walls, a mass of oil filtering material in the filter chamber, an air chamber below the filter chamber, an air outlet therefrom, an oil chamber beneath said air chamber and communicating therewith, a vertical inlet passage for the air having at the opening at the upper end thereof, a second vertical passage 65 communicating with the first at the bottom and adjacent the oil chamber, perforations in the wall, separating the oil chamber from the second said vertical passage and a substantially horizontal passage connected to said vertical passage and extending upon 70 the upper perforated wall of the filter chamber.

5. In a device of the class described, a filter chamber having perforate upper and lower walls, a mass of fibrous material in said chamber, an air chamber immediately below said filter chamber, an air outlet from said chamber having a downwardly turned flaring inlet nozzle, an oil chamber beneath and communicating with said air chamber, a substantially vertical air inlet passage adapted to receive air at its upper end, an air passage extending from the lower end 75 of the first said air passage upwardly to the upper perforate wall of the filter chamber, there being openings connecting said oil chamber with the latter said air passage.

ROBERT O. HENDRICKSON.
